UNITED STATES PATENT OFFICE

JOHN C. WILMOT, OF CHICAGO, ILLINOIS, ASSIGNOR TO VARIETY FIRE DOOR COMPANY, OF CHICAGO, ILLINOIS, A CORPORATION OF ILLINOIS

DOOR-LATCH RETAINER

Application filed March 11, 1927. Serial No. 174,669.

This invention relates to door latch retainers, more particularly to door latch retainers for elevator doors of the type which comprise a pair of vertical sliding sections, 5 which sections meet when the door is closed and move vertically away from each other in opening.

Doors of this sort are usually latched in closed position by latch bars, which are 10 spring projected from the sides of the door and engage stops suitably fixed to the vertical guides, for example. The outer ends of the latch bars usually ride up and down over the stops in the closing and opening 15 movement of the door, the stops usually being wedge-like or inclined to cam the outer ends of the bars inwardly and upon clearing the upper ends of the stops the bars are projected out into locking engagement there- 20 with.

The object of the present invention is the provision of a generally improved and simplified latch retainer that may be economically produced, conveniently installed 25 and advantageously employed in various door structures of this type and which will hold the latch bar out of engagement with the door stop in the opening and closing movement of the door so as to avoid the friction or contact of the latch bars, with the 30 stops, as the door is opened and closed and any wear or other undesirable results which might be produced thereby.

The invention is illustrated in the accompanying drawing in which,

Fig. 1 is a fragmentary elevation of a door showing an embodiment of the invention in connection therewith;

Fig. 2 is a somewhat enlarged section showing the door in closed position;

Fig. 3 is a similar view showing the door slightly open, as for example in its initial opening or final closing position;

Fig. 4 is a fragmentary elevation of a door 45 showing another embodiment of the invention with the door in closed position;

Fig. 5 is a fragmentary elevational view showing the door (Fig. 4) slightly open and the latch retainer in retaining position.

The present invention is not concerned

with the details of construction of the door, per se, and I shall, therefore, give just such a description of a particular form of slide door of this sort as will enable those skilled in the art to clearly understand the particular embodiment of the invention in connection therewith.

The form of door shown is particularly adapted for closing the usual doorways providing communication between an elevator 60 shaft and the various floors throughout the building and it is also useful in other connections.

The door comprises two panel members or sections 5 and 6 running in suitable vertical 65 guiding members 8. The lower edge 9 of the upper section 5 meets the upper edge 10 of the lower section 6 horizontally across the doorway when the door is closed and the sections 5 and 6 move vertically away from each 70 other in opening as well understood in the art.

The two panels or sections 5 and 6 are usually connected by means of suitable rods and flexible members such as chains which is 75 well understood in the art.

The latch mechanism comprises a latch plate or disc 12 pivoted centrally at 13 to the lower door section 6, just below the flange 14 along the upper edge of the lower door section. A suitable handle 15 is secured to the disc 12. The handle 15 projects radially from disc 12 and is adapted for turning or rotating the disc about its pivot 13. Pivoted to the disc or plate 12 at 16 and 18 are the two 85 latch bars or arms 19 and 20. The latch bars 19 and 20 extend generally horizontally toward opposite sides of the door and their free ends are adapted to project through the side flanges 21 of the lower door section and to 90 overlie suitable stops 25 when the door is closed. The stop 25 may be secured to the vertical guide member 8 as shown.

A spring 28 connected between the disc 12 and a bracket member 29 on the lower door 95 section 6 tends to turn or rotate the disc 12 in a counter-clockwise direction (Fig. 1) tending to urge the handle 15 into the position shown and the latch bars 19 and 20 into projected locking position.

To open the door the handle 15 is grasped and the disc 12 turned in a clockwise direction. This retracts the latch bars 19 and 20 inwardly until their outer ends clear the 5 stops or fixed abutments 25 whereupon the door sections are free to be moved apart or separated into open position.

For holding the latch bars in retracted position and against riding up over the inclined 10 surfaces of the stops 25 in the opening and closing movement of the door, the outer ends of the upper edges of the bars 19 and 20 are notched at 30 to provide an outwardly facing vertical shoulder 32. As the latch bar is retracted clear of the stop 25 and the door 15 opened by moving the sections 5 and 6 apart the outer end of the latch bar is swung up by spring means 35 and the shoulder 32 engaged at 36 (Fig. 3) with the side flange 21 at the 20 top of the opening 37 through which the latch bar extends.

Any suitable spring means may be employed at 35. That shown comprises a bracket 38 attached to the door section 6 beneath 25 the bar 20 with a plunger 39 mounted therein. The plunger 39 is headed at 40 with a spring 42 interposed between the head 40 and bracket 38, pressing the head 40 against the bar 20 and urging the bar 20 yieldingly upwardly about its pivoted connection at 18 with the operating disc 12. It is to be understood, of course, that where there are two latch bars as shown the spring and other means associated with each are the same so 30 that a description of one will suffice for both.

For releasing the retainer the bottom of each side of the upper door section 5 has a pin 45 fixedly secured therein at 46 for cooperation with the latch bars at opposite 40 sides of the door. The upper flange 14 of the lower door section 6 has openings 48 and the pins 45 are projected through these openings 48 as the door approaches its closed position and engage the latch bars 19 and 20 forcing 45 same downwardly against the spring or tension means 35 and releasing the shoulder 32 from the side flanges 21 of the lower door section, whereupon the latch bars are projected out over the stops 25 by the spring 28 and 50 lock the door in closed position.

Where the door is used in an elevator shaft suitable interlock means may be provided for preventing operation of the car when the door is open. The means shown comprises a motor 55 circuit for driving the elevator car and this circuit has conductors which lead to contacts 50, 52 in a box or housing 53. The housing 53 is shown mounted with its bottom wall 54 upon the stop 25 and its side wall 56 has 60 an opening 58 through which the adjacent end of the latch bar projects into the housing 53. A generally bell crank arm 60 pivoted at 61 within the housing 53 has a bridging contact 62 for bridging the contacts 50, 52 and 65 closing the motor circuit when the door is

closed. At its opposite end the arm 60 has a pair of fingers 63 with which the adjacent notched and tapered end 64 of the latch arm 40 cooperates to close the bridging contacts in the closed position of the door and to release the bridging contact so that it will open by gravity as the latch bars 19, 20 are retracted to open the door.

In the embodiment of the invention shown in Figures 4 and 5 an additional retainer bar 68 is employed instead of providing the shoulder 36 for engagement with the side flange of the door. The bar 68 is pivoted at 70 in a bracket 72 mounted at the top of the lower door section beneath the top flange thereof. The latch end of the bar 68 is turned down at 73 for engagement with suitable notches 74 in the upper edge of the bar 20' which corresponds with the bar 20 of Figs. 1, 2, 3. The pivot 70 is disposed off-center with respect to the bar 68 so that the latch end 73 of the bar will drop by gravity into one of the notches 74 as shown in Figure 5 as the bar 20' is retracted and the door opened.

For freeing the bar 68 as the door is closed 90 the upper section 5', has, as before, a pin 46' which engages the opposite horizontally turned end 80 of the bar 68 and swings the latch end 73 out of engagement with the notch 74, whereupon the bar is projected over 95 the stop 25' to lock the door closed, as before.

An interlock 82 may be employed as before, although, of course, the present invention may be embodied where there is no interlock.

I claim:—

1. In combination, a door comprising a first door section and a second door section, said sections being movable away from and toward each other in opening and closing, a stop having relatively fixed position along the first door section, a latch bar mounted on said first door section and adapted to be engaged with and released from said stop, means operable upon opening the door for retaining said latch in released position and means mounted on the second door section and operable upon closing the door for releasing said retaining means.

2. In combination, a door comprising a pair of door sections movable away from and toward each other in opening and closing, a stop, a latch bar mounted on the door and adapted to be engaged with and released from said stop, means for retaining the latch in released position and means operated by relative movement between said door sections and disposed wholly on the door and independent of the lintel for releasing said retaining means.

3. In combination, a door comprising a pair of door sections movable away from and toward each other in opening and closing, a latch bar mounted on one door section and having a latching position for holding the door closed, said latch bar having a released

position, means for retaining the latch bar in released position and means on the other door section for releasing said retaining means as the door is closed.

5. In combination, a door comprising a pair of door sections movable away from and toward each other in opening and closing, a latch bar mounted on one door section and having a latching position for holding the door closed, said latch bar having a released position, means for retaining the latch bar in released position and means on the other door section for releasing said retaining means as the door is closed, the lower door section having a side flange with an opening through which the latch bar projects and a top flange having an opening through which the releasing means is adapted to be projected to release said bar.

20. In combination, a door comprising upper and lower door sections movable vertically away from and toward each other in opening and closing, a stop, a disc pivoted on the lower section and provided with an operating handle, a latch bar pivoted to said disc, a spring for projecting said bar from the side of the door into cooperation with said stop, means on the lower door section for retaining said bar against projection and means on the upper door section for releasing said retaining means.

6. In combination, a door comprising upper and lower door sections movable vertically away from and toward each other in opening and closing, a stop, a disc pivoted on the lower section and provided with an operating handle, a latch bar pivoted to said disc, a spring for projecting said bar from the side of the door into cooperation with said stop, the latch bar having a notch forming a shoulder for engaging the side flange of the lower section to retain said bar against projection, a spring pressing the bar to engage said shoulder with said flange and pin means on the upper section movable through an opening in the upper flange of the lower section for releasing said retaining means.

7. In combination, a door comprising upper and lower door sections movable vertically away from and toward each other in opening and closing, a stop, a disc pivoted on the lower section and provided with an operating handle, a latch bar pivoted to said disc, a spring for projecting said bar from the side of the door into cooperation with said stop, a retaining bar pivoted on the lower section and engageable with the latch bar to hold same against engagement with the stop and a pin on the upper section movable through an opening in the upper flange of the lower section for releasing said retaining bar.

8. In combination, a pair of door sections movable to open and closed positions, latch means for holding the door closed, means for

retaining said latch means out of door latching position and means operated by the closing of the door and disposed wholly on the door and independent of the adjacent lintel for releasing said retaining means.

In witness whereof, I hereunto subscribe my name this 7 day of March, 1927.

JOHN C. WILMOT.
